Patented Feb. 17, 1914.

UNITED STATES PATENT OFFICE.

ANDREW M. SHUHANY, OF CHELMSFORD, MASSACHUSETTS.

AERIAL TORPEDO.

1,087,192.

Specification of Letters Patent.

Patented Feb. 17, 1914.

Application filed July 11, 1913. Serial No. 778,450.

To all whom it may concern:

Be it known that I, ANDREW M. SHUHANY, a subject of the United Kingdom of Great Britain and Ireland, residing at 5 Chelmsford, in the county of Middlesex and Commonwealth of Massachusetts, have invented a certain new and useful Improvement in Aerial Torpedoes, of which the following is a specification.

10 This invention relates to aerial torpedoes or torpedoes designed to be dropped or thrown from flying machines, as aeroplanes and air-ships or dirigible balloons.

The object of said invention is to secure 15 in such torpedoes greater certainty of discharge, accuracy of flight and safety in loading and handling, and to prevent accidental or premature discharge.

In the accompanying drawing Figure 1 is 20 an elevation of the charging side of the torpedo, the cover of the body or compartment which carries the explosive charge being removed, and the weight and drag and adjacent parts of the body being in central longitudinal section; Fig. 2, a section of the 25 body on the line 2-2 in Fig. 1; Fig. 3, a front elevation of the torpedo; Fig. 4, a longitudinal central section of the firing-pin guide, showing said pin and its retracting spring in side elevation; Fig. 5, a side elevation of the plunger and its guide-plug and check-nut and of the safety pin.

The body A of the torpedo is a box of any suitable material, the pieces of which 35 when the body bursts will serve as missiles, preferably, of metal as cast-iron, and preferably rectangular or, at least, having a flat side on which it may rest while being filled. The cover B of the box is rabbeted at b (Fig. 2) and the adjacent side-edges of the 40 box A are rabbeted at a to fit the cover which is retained on the box by bolts or screws C which pass through the cover at right angles to the face of said cover, and 45 are tapped into the adjacent faces of the two rabbets as indicated in Figs. 1 and 2 and into the sides a² of the same. Opposite sides a² have on their inner faces grooves or ways a³ which receive the ends of a sliding cross-bar D, which is perforated midway between 50 its ends to receive and fit a cartridge shell

E filled with a suitable explosive and having a primer e filled with material explosive by percussion. The cartridge is retained in the holding-bar D by suitable retaining means as by a cap-screw F which turns in said bar until its head rests on the flange e¹ of said cartridge. Two screws G G parallel with each other and with the ways a³ a² pass through and are threaded into the 55 bar D near its ends and are just long enough to reach from the inner face of the cover B to the inner face of the opposite side a⁴ of the box A when said cover is fastened in place, so that by turning said screws G G 60 the primer e or a portion of the flange e¹, if the cartridge be a rim-fire cartridge, may be brought into exact alignment with the firing-pin H hereinafter described. A weight I, preferably of cast-iron, having a tapering 65 shape to cleave the air and represented as a frustum of a rectangular pyramid, is rigidly secured by screws i i to the front end a¹ of the box A and has an axial hole i¹ in alignment with a perforation a⁵ in the 70 box A.

The gravity of the substantially solid weight I causes the torpedo, when let go, to descend vertically with said weight I in advance.

Before the weight I is secured to the box A, the rear end of the tubular firing-pin guide J (Figs. 1 and 4), the end at the right in Fig. 4, said guide containing the firing-pin H and its retracting spring L, is inserted in the perforation a⁵ up to the collar j and the guide-retaining spring M is placed in the hole i¹ against an annular shoulder i² in said hole i¹ and the other or lower end, of said guide is inserted in said spring M 85 and hole up to said collar j, the compression of said spring between said shoulder i² and collar j holding said collar against the front of the box A.

The guide J closely fits the perforation a⁵ and the firing-pin H has a sliding fit in said guide and is normally held out of contact with the primer e of the cartridge by a spiral wire spring L surrounding said pin and compressed between the bottom j¹ of the 95 counterbored recess j² and a collar j³ on said pin, said spring normally holding said

collar j^2 , against an annular bearing plug j^1 secured in the front end of said guide.

The plunger N has bearings in the reduced middle portion i^3 of the hole i^1 and in 5 an externally-threaded plug n turned in the front end of said hole and prevented from becoming loose by a check-nut n^1 . The plunger is normally kept out of contact with the firing-pin by a spiral spring n^2 10 rounding said plunger and compressed between said reduced part i^3 of the hole i^1 and the collar n^3 .

For greater security in loading and handling the torpedo, a safety pin O is passed 15 through a transverse hole in the plunger close to the front end of the bearing plug, said pin being represented as smaller at the point o for easy introduction and provided on its larger part with a screw-thread o^1 20 to engage a corresponding thread in said hole. The plunger at its front end has an enlarged head n^4 .

For greater directness of flight and to 25 keep the weight in advance at all times, a drag P is secured to the rear end of the body A by screws p^0 p^0 , said drag consisting of a box of light material as wood and having a cover p hinged thereto at p^1 p^1 and secured when closed by a latch p^2 . This 30 drag or box is substantially empty of everything but air, although it may be used to contain a few coils of a time fuse Q when desired. The safety-fuse Q ends within the body or box A in a cartridge or case q containing any desired highly-explosive material so that if the torpedo is dropped over 35 water or a bog and might fail to explode, owing to the little resistance offered by these, or should strike a glancing blow on rock or other hard material between the front and rear of the weight and be thrown on its side without the head of the plunger striking, the explosion of the torpedo will be certain. The fuse Q goes through holes a^0 p^3 p^4 to the 40 outside of the torpedo so that it may be lighted before dropping the torpedo. The body A is loaded with explosive material and may also contain missiles and highly inflammable material, like Greek fire, to create 45 confflagrations.

The construction of the firing-pin guide and its coöperating parts allows said guide to be pushed forward until the firing pin projects therefrom, so that the firing-pin 50 may be grasped by the thumb and finger and brought in contact with the cartridge or sufficiently near to it to determine the correct position of the primer or rim of the cartridge with reference to the firing-pin.

60 I claim as my invention:

1. The combination in an aerial torpedo, of a hollow body adapted to receive explosive material, a tapering weight secured to the front of said body, and a drag of lighter

material than said body secured to the rear 65 of said body, said drag comprising a substantially empty box larger in cross-section than said body.

2. The combination in an aerial torpedo, of a body consisting of a hollow box adapted 70 to receive explosive material, a metallic weight secured to the front of said body, and a drag consisting of a substantially empty box secured to the rear of said body and projecting beyond the sides of the same. 75

3. The combination in a torpedo, of a hollow body having a perforated front, means for holding a cartridge in said body in alignment with said perforation, a weight rigidly secured to the front of said body and 80 having a hole in alignment with said perforation, a firing pin arranged in said perforation and hole, means for guiding said firing pin, a spring normally to hold said firing pin out of contact with said cartridge, 85 a plunger arranged in said hole and projecting from the front of said weight and means for normally holding said plunger out of contact with said firing-pin.

4. The combination in a torpedo, of a hollow body having a perforated front, a weight secured to the front of said body and having a hole therethrough in alignment with said perforation, said hole having a middle portion of reduced diameter, a tubular firing-pin guide arranged in said perforation and hole and having in its front portion a counter-bored recess, a firing pin longer than said guide, and provided with a collar, a spring arranged in said recess and 100 compressed between the rear end of said recess and said collar, a bearing-plug for said firing-pin secured in the front end of said guide, a plunger having a collar arranged in said hole in alignment with said firing-pin, 105 a spring compressed between said last named collar and the annular shoulder at the reduced part of said hole, an externally-threaded plug through which said plunger projects in front of said weight, and means 110 for preventing accidental turning of said plug.

5. The combination in a torpedo, of a hollow body having a perforated front, a weight secured to the front of said body and 115 having a hole therethrough in alignment with said perforation, said hole having a middle portion of reduced diameter, a tubular firing-pin guide arranged in said perforation and hole, and having in its front portion a counter-bored recess, and having a 120 collar, a spring surrounding said guide in front of said collar and compressed between said collar, and a shoulder in said hole normally to hold said collar against the front 125 of said body, a firing-pin longer than said guide and arranged in said guide and provided with a collar, a spring arranged in

said recess and compressed between the rear end of said recess and said last named collar, and adjustable means for holding a cartridge in said body, to enable said guide to be pushed forward and said firing-pin to be drawn backward to observe the alinement of said pin with said cartridge.

In witness whereof, I have affixed my signature in presence of two witnesses.

ANDREW M. SHUHANY.
